UNITED STATES PATENT OFFICE

153,122

DESIGN FOR A CAMISOLE OR SIMILAR ARTICLE

Harry Colton, New York, N. Y.

Application May 6, 1948, Serial No. 146,198

Term of patent 3½ years

(Cl. D3—25)

To all whom it may concern:

Be it known that I, Harry Colton, a citizen of the United States of America, residing in New York, county of New York, and State of New York, have invented a new, original, and ornamental Design for a Camisole or Similar Article, of which the following is a specification, reference being had to the accompanying drawing, forming part thereof.

Fig. 1 is a front view of a camisole or similar article, showing my new design.

Fig. 2 is a rear view thereof.

Fig. 3 is an enlarged view of a portion of the embroidery shown in Figure 1.

I claim:

The ornamental design for a camisole or similar article, substantially as shown.

HARRY COLTON.
